UNITED STATES PATENT OFFICE.

THEODORE HAVILAND, OF AMBAZAC, FRANCE.

DESIGN FOR A PLATE.

SPECIFICATION forming part of Design No. 22,440, dated May 16, 1893.

Application filed February 28, 1893. Serial No. 464,110. Term of patent 7 years.

To all whom it may concern:

Be it known that I, THEODORE HAVILAND, a citizen of the United States, residing at Ambazac, in the Department of Haute-Vienne and Republic of France, have invented and produced a new and original Design for Dishes; and I do hereby declare the following to be a full, clear, and exact description of the same, reference being had to the accompanying drawings, forming a part thereof.

The design is shown in the figure of the drawings as embodied in a plate having the shape shown in the drawings, and provided with a V shaped flange or periphery on the under side of the periphery or circumference of the plate.

In Figure 1 is shown a view of the under side of the plate.

A represents the elevations or V shaped flange which passes around the entire circumference. In the sectional view Fig. 2 this flange is shown by a. In order to make the flange more prominent a slight hollow is made at B.

What I claim is—

The design for plates substantially as herein shown and described.

In testimony whereof I affix my signature in presence of two witnesses.

THEODORE HAVILAND.

Witnesses:

L. GREZILLIE,
ARNAUD ANDRIEUX.
